UNITED STATES PATENT OFFICE.

HOWARD G. MACDONALD, OF WILKINSBURG, PENNSYLVANIA, ASSIGNOR TO WESTING-HOUSE ELECTRIC AND MANUFACTURING COMPANY, A CORPORATION OF PENNSYLVANIA.

CIRCUIT-INTERRUPTER.

1,206,347.

Specification of Letters Patent. Patented Nov. 28, 1916.

Application filed February 15, 1912. Serial No. 877,866.

To all whom it may concern:

Be it known that I, HOWARD G. MACDONALD, a citizen of the United States, and a resident of Wilkinsburg, in the county of 5 Allegheny and State of Pennsylvania, have invented a new and useful Improvement in Circuit-Interrupters, of which the following is a specification.

My invention relates to circuit interrupters and it has particular reference to devices 10 of the oil-immersed type which are provided with means for both manual and automatic release.

One of the objects of my invention is to 15 provide a device of the above-indicated class which shall be simple and durable in construction and effective and reliable in operation, and shall also embody an operating mechanism of the so-called "non-closable-on-overload" type to be actuated by means 20 of an operating handle which is located at a distance from the circuit interrupter and is associated therewith by suitable mechanical connecting means.

Another object of my invention is to provide adequate means whereby the position 25 of the remotely-located operating handle may positively indicate whether the circuit interrupter is open or closed, irrespective of 30 whether the interrupter is tripped automatically or manually.

Heretofore, the usual practice has been to either locate the restraining latch and tripping mechanism of a remotely controlled 35 circuit interrupter upon the switchboard in combination with the operating handle, in which case, the operating handle may be made to serve the purpose of an indicator, or the latch and tripping mechanism have been associated with the circuit 40 interrupter proper, in which case the operating handle does not indicate the condition of the interrupter, and auxiliary signal lamps have been employed.

With the first arrangement, when the 45 interrupter is automatically tripped, an appreciable time exists between the instant of tripping and the actual opening of the interrupter, which is caused by the operation 50 of the mechanical connecting means between the operating handle and the interrupter. Furthermore, with this arrangement, addi-

tional control wiring to the switchboard is required.

With the second arrangement, the interrupter responds immediately to abnormal circuit conditions and, although no unnecessary time interval exists between its release and its actual opening, still, the remotely-located operating handle gives no accurate 60 indication of the condition of the breaker, and signal lamps are relied upon, which necessarily complicates the circuit connections and reduces the reliability.

According to my present invention, I 65 provide a circuit interrupter of the "non-closable-on-overload" type, and I arrange the component parts of the operating mechanism in such manner that the restraining latch and the automatic tripping device may 70 be located within the interrupter. Furthermore, the position of the operating handle indicates with reliability whether the interrupter is open or closed. Thus, the disadvantages and difficulties heretofore encountered 75 in connection with apparatus of this type are overcome and an interrupter which is simple in construction and reliable in operation is provided.

My invention may best be understood by 80 reference to the accompanying drawings in which—

Figure 1 is a view, partially in elevation and partially in section, of a circuit interrupter embodying my invention, Fig. 2 is 85 an enlarged plan view of a portion of the operating mechanism shown in Fig. 1, and Fig. 3 is a view, partially in section and partially in side elevation, of the operating mechanism shown in Fig. 2. 90

Referring to the drawings in detail, the apparatus here shown comprises a plurality of stationary contact members 1, a plurality of coöperating movable contact members 2, an operating mechanism 3 embodying a compound operating lever 4, a plurality of latches 5 and 6, automatic tripping devices 7, a remotely-disposed operating handle 8 and a mechanism 9 for mechanically connecting said operating handle with said 100 compound operating lever.

The coöperating stationary and movable contact members 1 and 2, respectively, are preferably of the butt-contact type, al-

though any other suitable construction may be employed, the stationary contact members 1 being supported at the lower ends of suitable bushings 10 which are adapted to protect and insulate the main circuit conductors (not shown) from the cover 11 of the containing tank 12 in which the contact members 1 and 2 are immersed in oil. The movable contact members 2 are arranged in a co-operative relationship with the contact members 1 in the usual manner and are suitably attached to the lower end of a rod 13 which is pivotally associated with the operating mechanism 3.

15. The operating mechanism 3 comprises a lever 14, one end of which is pivotally connected to the upper end of the suspension rod 13 and the other end of which is similarly connected to the upper end of a guide link 15. The guide link 15 is pivotally mounted upon a shaft 16 that is carried at the end of a bracket member 17 with which the cover 11 is provided, and said guide link 15 projects slightly below its pivotal support and is provided with a boss or lug 18, for a purpose to be hereinafter set forth.

In order to assist in the operation of the movable contact members 2, I provide a toggle mechanism comprising a link 19 which is pivotally connected to the lever 14 at a point substantially midway between its ends and an arm 20 that forms an integral part of a main lever 21 which cooperates with a bifurcated auxiliary lever 22 to form 35 the compound operating lever 4 hereinbefore mentioned and more fully set forth hereinafter.

The integrally associated arm 20 and lever 21, and also the auxiliary lever 22, are pivotally supported upon the shaft 16 and associated with the arm 20 is a projecting member 23 that is provided with an adjustable stop 24, the latter being adapted to engage the lug or boss 18 on the link 15 in order to 45 permit any desired adjustment of pressure between the co-operating contact members 1 and 2.

One end of a guiding link 26 is pivotally connected to the lever 14 upon the pin which 50 serves as the pivotal connection for the link 19, and the other end is similarly associated with the upper end of an upwardly projecting member 27 which forms a part of the cover 11, said link 26 serving to constrain 55 the movements of the operating mechanism within prescribed limits.

The main and auxiliary levers 21 and 22, respectively, are connected together to form the compound operating lever 4 by means of 60 the latch 5 that is pivotally supported upon the auxiliary lever 22 and engages a pin 28 that is carried at the end of the lever 21. The latch 5 is also provided with an arm 29 that projects above hammer rods 30 which

are severally associated with movable core 65 members 31 of the electro-magnetic tripping devices 7. Each of the tripping devices 7 is supported by suitable bracket members 34 and further embodies a stationary core member 32 and an energizing winding 33.

70 In order to restrain the compound operating lever 4 in its closed position, whereby the co-operating contact members are maintained in engagement, the latch 6 is provided and is pivotally mounted upon a pin 75 35 and adapted to engage a detent 36 on the auxiliary lever 22. The latch 6 is provided with a spring 37 which is disposed between a portion of a supporting bracket 38 and a downwardly projecting member 39 forming 80 a part of the latch 6. The spring 37 is adapted to maintain said latch 6 in engagement with the detent 36. The latch 6 is further provided with a projecting arm 40 to be engaged by the upper end of a rod 41 85 that projects through an inclosing casing 42 which envelops and protects the entire operating mechanism, the lower end of the rod 41 being provided with a suitable button or handle 43. An extension member 44 also 90 constitutes a part of the latch 6 and projects upwardly between arms 45 of a bifurcated portion that is disposed approximately in the middle of the lever 21. A pin 46 is carried between the arms 45 just referred to, 95 and said pin engages the extension member 44 when the compound lever 4 and operating mechanism are in their closed positions. The extension member 44 serves as a cam during the opening operation of the interrupter and, 100 by reason of its peculiar shape and its engagement with the pin 46, the release of the latch 6 from the detent 36 is effected when the lever 21 moves into its upper position.

105 Within the casing 42, and fixed to the shaft 16, is an arm 47 having a slot or recess 48 in its free end to receive one end of a rod 49 which projects through the several arms of the bifurcated auxiliary lever 22 and is disposed parallel to the shaft 16. The shaft 110 16 projects through the casing 42 and its outer end carries a bell crank lever 50, one arm 50^a of which carries a counterweight 51, while the outer end of the other arm 51^a is connected by a pin and slot connection 115 52 to a vertically disposed rod 53. The rod 53 is provided with a projecting arm 54 which is adapted to engage the button 43 at the lower end of the rod 41 under certain conditions, as will be hereinafter set forth. 120

125 The operating handle 8 is pivotally mounted upon a suitable switchboard panel 55 that is remotely located with respect to the circuit interrupter proper, and said handle is mechanically connected to the rod 127 53 by means of connecting rods 56 and 57 and bell crank levers 58 and 59. Obviously, any other suitable mechanical connection be-

tween the operating handle and the operating mechanism of the interrupter may be employed and, inasmuch as the construction and operation of such mechanical connecting means are old and familiar to those skilled in the art, no detailed description of the same is considered necessary.

Assuming the interrupter to be closed and the various parts of the apparatus to occupy the positions shown, the automatic release of the interrupter is accomplished as follows: When, in accordance with predetermined conditions and adjustments of the tripping devices 7, sufficient current traverses the same to energize either of the movable core members 31, one of the hammer rods 30 is projected against the arm 29 of the latch 5 and the main lever 21 is thereby released. Thus, the operating toggle formed by the link 19 and the arm 20 is allowed to collapse, whereby the separation of the coöperating contact members 1 and 2 is effected in a well known manner.

During the opening operation of the interrupter, the operating lever 21 is rotated in a clockwise direction into its upper position and, in so doing, the latch 6 is released from the detent 36 on the auxiliary lever 22 by reason of the coöperative engagement of the pin 46 and the extension member 44 of said latch. Hence, the counterweight 51, which is rigidly associated with the shaft 16, causes said shaft to be rotated in a clockwise direction and, inasmuch as the arm 47 is pinned thereto and is, furthermore, mechanically associated with the bifurcated auxiliary lever 22 by means of the rod 49, the lever 22 is thereby moved upwardly in a clockwise direction into its open position. In this position, the main and auxiliary levers 21 and 22, respectively, are again connected together by means of the latch 5 and occupy the positions shown in dot and dash lines in Fig. 1.

During the upward movement of the auxiliary lever 22 the rod 53 is drawn upwardly, on account of its connection with the arm 51^a of the bell crank 50 which is pinned to the shaft 16. It is evident, therefore, that, through the agency of the connecting rods 56 and 57 and bell crank levers 58, hereinbefore set forth, the operating handle 8 is raised into its upper position, as indicated in dot and dash lines in Fig. 1, and hence, serves to indicate that the interrupter is open.

In order to close the interrupter, the operating handle 8 is forced downwardly and the movement thereof is transmitted, through the connecting mechanism just referred to, to the shaft 16 and thence to the auxiliary bifurcated lever 22, through the agency of the arm 47 and the rod 49.

The compound lever 4, comprising the main

and auxiliary levers 21 and 22, respectively, 65 which are now connected by the latch 5, is thus moved downwardly into its closed position and, if no abnormal circuit conditions obtain, the latch 6 engages the detent 36 and maintains the compound lever 4 in its closed 70 position, the various parts of the apparatus then occupying positions shown in full lines in the accompanying drawings. During the downward movement of the compound lever 4, the operating toggle is forced toward its 75 dead center position, thereby raising the lever 14 and, hence, effecting the closure of the coöperating contact members 1 and 2. However, in case abnormal circuit conditions exist when the interrupter is being 80 closed, the one or the other, or both, of the tripping devices 7 will be energized and one or both of the associated hammer rods 30 will be projected against the latch 5, whereby said latch is disengaged from the pin 85 28. In this way, the main operating lever 21 is immediately released, and the interrupter is again opened in the manner just described in detail. It is evident, therefore, that it is impossible to hold the interrupter closed 90 under predetermined abnormal circuit conditions.

In case manual tripping of the interrupter is desired, the operator has only to raise the operating handle 8 into its upper position, 95 whereby the rod 53 is moved upwardly through the agency of the interconnecting mechanism 9 and the arm 54 associated with the said rod is caused to engage the button 43 at the lower end of the rod 41. The rod 100 41, therefore, is brought into engagement with the arm 40 of the latch 6, whereby said latch is released from the detent 36 and the compound lever 4, as a unit, is released. By reason of the counter-weight 51 and the 105 weight of the interrupter parts, the operating toggle is permitted to buckle, thereby allowing the coöperating contact members of the interrupter to separate. The compound lever 4 is thus raised into its upper 110 position.

It will be understood that, as the operating handle 8 is raised and a corresponding movement is given the rod 53, said movement has no direct effect upon the operating mechanism of the interrupter, except through the agency of the tripping rod 41, inasmuch as the rod 53 is associated therewith by means of a pin and slot connection which allows considerable lost motion.

When the compound lever 4 reaches its upper position, the pin, which forms a part of the pin and slot connection hereinbefore mentioned, comes into engagement with the upper portion of the slotted rod 53 and thereby retains said rod and the operating handle, in their upper positions. Thus, the operating handle 8 again serves to indicate

that the interrupter is open. The closing operation of the interrupter may then be effected in the manner hereinbefore set forth.

5 While I have shown and described a circuit interrupting device of specific structural details and arrangement and location of parts, those skilled in the art will readily understand that various modifications may 10 be effected therein without departing from the spirit and scope of my invention, and I desire that only such limitations shall be imposed as are indicated in the appended claims.

15 I claim as my invention:

1. In a circuit interrupter, the combination with relatively movable contact members, an operating mechanism for said movable members embodying a pivotally 20 mounted compound operating lever, means associated with said lever for latching the component members thereof together, and means for restraining said compound lever in its closed position, of means for releasing 25 said latching means and a cam member associated with said restraining means and co-operating with one of said component members for subsequently releasing said restraining means.

30 2. In a circuit interrupter, the combination with relatively movable coöperating contact members, an operating mechanism for the movable members, a compound operating lever associated with said mechanism, and means for restraining said lever in its closed position and for connecting the component parts thereof together, of means for automatically releasing the component parts of said compound lever in succession 35 and for manually releasing the compound lever as a unit.

35 3. In a circuit interrupter, the combination with relatively movable coöperating contact members, an operating mechanism 40 for the movable members, and a compound operating lever associated with said mechanism and comprising main and auxiliary levers, of means for latching said main and auxiliary levers together, means for releasing 45 said latching means, a second means for latching said compound lever in its closed position and a cam member forming a part of said second latching means and normally adapted to engage a portion of said auxiliary 50 lever for automatically releasing said second latching means subsequent to the release of 55 said first latching means.

40 4. In a circuit interrupter, the combination with relatively movable coöperating contact members, an operating mechanism for the movable member and a compound operating lever associated with said operating mechanism and comprising a main lever and an auxiliary lever having an opening

therein and a pin projecting transversely 65 across said opening, of a latch for connecting said levers, means dependent upon predetermined circuit conditions for releasing said latch, a second latch for restraining said main lever in its closed position, means 70 for manually releasing said second latch, and a cam constituting a part of said second latch and projecting normally through said opening and in engagement with said pin for effecting the automatic release of said 75 second latch under predetermined conditions.

5. In a circuit interrupter, the combination with relatively movable coöperating contact members, an operating mechanism 80 for said movable members embodying an operating toggle and a main operating lever associated therewith, of an auxiliary lever having a transverse engaging member, means for latching said levers together, a 85 latch for restraining said auxiliary lever and its associated main lever in their closed positions, a cam constituting a projecting portion of said latch and adapted to coöperate with said engaging member, electro-responsive means for releasing said latching means, whereby the opening of the interrupter is 90 effected and the said engaging member operates said restraining latch to cause said main levers to be released. 95

6. In a circuit interrupter, the combination with relatively movable coöperating contact members, an operating mechanism for said movable members, and a compound operating lever for said mechanism, comprising coaxially pivoted main and auxiliary lever members, of means for connecting said lever members together and for restraining said members in their closed positions, and means embodying a cam normally engaging 100 said main lever member for automatically releasing said restraining means under predetermined conditions. 105

7. In a circuit interrupter, the combination with movable and stationary contact members, and a compound operating lever for the movable contact member, of means for restraining the said lever in its closed position and for connecting the component parts thereof together, means for automatically releasing the component parts of the lever in succession, and an operating means for actuating the said lever and for manually releasing it as a unit. 110 115

8. In a circuit interrupter, the combination with relatively movable coöperating contact members, and an operating mechanism for the movable members, of means for restraining said mechanism, means for automatically releasing said restraining means 120 under predetermined conditions and for preventing the restraint of said interrupter when closed under said conditions, an oper- 125

ating means for actuating said mechanism and for manually releasing said restraining means, and a pin and slot connection between said operating means and said mechanism for causing said operating means to indicate the condition of the interrupter.

In testimony whereof, I have hereunto

subscribed my name this 13th day of Feb., 1912.

HOWARD G. MacDONALD.
